UNITED STATES PATENT OFFICE

137,054

DESIGN FOR A DEODORANT

Samuel Levy, New York, N. Y.

Application August 13, 1943, Serial No. 110,906

Term of patent 14 years

To all whom it may concern:

Be it known that I, Samuel Levy, a citizen of the United States and a resident of the county, city, and State of New York, have invented a new, original, and ornamental Design for a Deodorant, of which the following is a specification, reference being had to the accompanying drawing, forming part thereof, in which

I claim:

The ornamental design for a deodorant, as shown.

SAMUEL LEVY.
